UNITED STATES PATENT OFFICE.

VICTOR E. EDWARDS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

ROLLING-MILL.

1,290,942.

Specification of Letters Patent. Patented Jan. 14, 1919.

Application filed July 31, 1915. Serial No. 43,047.

To all whom it may concern:

Be it known that I, VICTOR E. EDWARDS, a citizen of the United States, residing at Worcester, in the county of Worcester and 5 Commonwealth of Massachusetts, have invented a new and useful Improvement in Rolling-Mills, of which the following, together with the accompanying drawings, is a specification.

10 The present invention relates to a rolling mill, designed for the continuous reduction of metal rods or bars, and has particular reference to the provision of novel and improved apparatus for the production of bars 15 of accurate circular cross section, known as "rounds", according to the method set forth and described in my copending companion application Serial No. 873,463, filed November 23, 1914.

20 The arrangement and disposition of instrumentalities found necessary for the successful carrying out of said method, together with the various refinements of practice introduced for the above purpose, are fully 25 set forth in the following description of my invention, reference being had to the accompanying drawings, in which—

Figure 1 is a plan view of the apparatus embodying the invention.

30 Fig. 2 is a view of the same in side elevation.

Fig. 3 is a view of the same in end elevation, from the right hand end of Fig. 1.

35 Fig. 4 is an enlarged fragmentary sectional view, taken on line 4—4, Fig. 1.

Similar reference characters refer to similar parts in the different figures.

As fully set forth in the aforesaid application covering my improved method for the 40 production of accurate "rounds", the continuous production of a "guide round", having a cross-sectional area slightly in excess of the cross-sectional area of the desired "round", is first contemplated; the further continuous 45 reduction of said oversize "round", under conditions which minimize the opportunity for error to arise by reason of the success-

sive changes in the shape of the material during said reduction, forms the subject matter of the aforesaid method.

50 In the accompanying drawings, I have indicated diagrammatically at 1, a stand of rolls representing the finishing end of a "guide mill" designed for the continuous production of a bar or rod having a slightly 55 greater cross-sectional area than the bar which it is desired eventually to produce. In advance of the rolls 1, is located a stand or housing 2, providing sets of rolls designed for the final reduction of the material according to my improved method, the novel 60 details of said stand of rolls 2 being fully set forth and described in another copending companion application, Serial No. 43,132, filed August 2, 1915.

65 In the drawings of the present application, the said stand 2 is shown as elevated above the level of the stand 1, merely for purposes of construction, in connection with an elevated cooling bed, not shown; it is obvious that the two stands may be disposed at 70 the same level.

75 Between the stands 1 and 2 a framework 3 supports an elongated open trough 4 preferably made in sections, as shown, and providing a shallow channel having its longitudinal axis inclined to coincide approximately with a line connecting the pass of stand 1 with the first pass of stand 2. The rear side of the trough 4 provides an 80 standing vertical wall 5 which effectually restrains movement of the rod out of the trough in the direction of said wall. The front side of the trough, however, is only slightly raised above the floor of the trough, 85 by a wall 6 which provides a downwardly and forwardly inclined lip or extension 7 throughout the length of the trough. An inclined plate 8, preferably made in sections, and forming a continuation of the lip 80 or extension 7, extends downwardly to a horizontal shelf 9 also preferably made in sections, which runs the entire length of trough 4. An inclined section 10 of the

shelf 9 extends from the forward end of the latter and slopes down gradually to the floor of the mill.

As shown in Fig. 1, the trough 4 assumes a slight outward bulge, or deviation from the straight line joining the passes of the two stands of rolls, this convexity of the trough being provided in order to assist the initial movement of the metal over the low wall 6, and onto the plate 8, in the event of an overfeed of the rod by the rolls of stand 1.

At its forward end the inclined plate 8 supports a curved guide 11, of substantially channel formation, the rear or convex side 15 of which serves to redirect the metal which constitutes such an overfeed, toward the first pass of stand 2. The guide 11 is carried across the forward lower corner of inclined plate 8, and has a straight continuation 12, 20 rising from the inner edge of the inclined section 10 and from the floor of the mill. Rising from the outer edges of shelf 9 and inclined section 10 and from the floor of the mill are the vertical walls 13 and 14 parallel with the wall 12, which serve to confine 25 the loop formed by the overfed metal.

Between the forward end of trough 4 and the stand 2, the framework of the mill supports a "snap" shear 15, of the general type shown in United States Letters Patent 30 to Thomas M. Jewell, No. 966,557, August 9, 1910. The supporting framework of the shear 15 provides a flaring mouth for the reception of the rod, one side 16 of which is in alinement with the rear wall 5 of trough 4, while the other side 17 forms a continuation of the guide 11, to facilitate the passage through the shear, of the metal forming the overfeed loop. As fully set 35 forth in the specification of the aforesaid patent to Jewell, the operation of said shear is effected by the manipulation of a lever 18 to swing the blades of the shear into contact with the advancing rod. When the 40 said blades have once engaged the rod, the movement of the rod itself serves to draw the cutting edges together, effecting a complete severance of the rod. Upon emerging 45 from the passes of stand 2, the rod is received within a conveying trough 19, the 50 sides and bottom of which provide a plurality of recesses 20 as shown in Fig. 4. The trough 19 leads the rod through a second "snap" shear 21, which is a duplicate, 55 in operation, of the shear 15. Emerging from the shear 21 the finished rod passes onto a cooling bed, not shown, of ordinary construction.

It will be understood that the oversize rod 60 in its passage from the final stand of rolls 1 of the guide mill to the passes of stand 2, will be supported in the trough 4, until the overfeed of the metal by the rolls 1 causes

it to leave the trough and to form a loop upon the plate 8 and shelf 9. The contour 65 of such a loop is represented, for example, by the broken line 22, Fig. 1, or by the broken line 23, it being clear that the size of the same is determined by the amount of overfeed imparted by the rolls 1. The walls 70 12, 13 and 14 prevent the spreading of the loop onto the floor of the mill, while the guide 11 controls the formation of the loop and insures the delivery of the metal therein to the rolls of stand 2, in a direction approximately coinciding with the axes of the 75 passes of said rolls.

In carrying out the method of the aforesaid copending application Serial No. 873,463, not only is the control of the free 80 overfeed loop in the manner above described most essential, but it is a requisite to the accurate reduction of the rod by the stand of rolls 2, that the oversize rod produced in the guide mill stand 1 be approximately round 85 in cross-section, to enable the rolls of housing 2 to operate properly thereon. The shear 15 is utilized advantageously to sever a short sample from the rear end of a rod so that the product of the guide mill can be 90 tested for accuracy. In this manner it can be determined whether or not the passes of the guide mill are suitably adjusted to give the desired cross-sectional shape, capable of being successfully and accurately reduced 95 by the passes of stand 2, before any subsequent rods are run through the mill.

In the same way, the snap shear 21 is operable to sever a sample from the rear end of a rod emerging from the passes of 100 stand 2, in order to ascertain the accuracy of the operation performed by the rolls of said stand, before the succeeding rod is run through said rolls. The recesses 20 of the trough 19 enable the sample to be seized 105 with tongs and withdrawn, for the purpose of testing the accuracy of the same with calipers, or the like.

I claim:

1. In a rolling mill, the combination with 110 separated stands of reducing rolls, having their passes approximately in alinement, of a trough for conveying the metal in its passage between said stands, said trough deviating from the line joining the passes of 115 said stands whereby an overfeed of metal is caused to occur in a predetermined direction.

2. In a rolling mill, the combination with 120 separated stands of reducing rolls, of a trough for conveying the metal in its passage between said stands, one side of said trough being relatively low, and means, operable in the event of an overfeed of metal 125 between said stands, whereby said overfeed is directed over said low side of the trough.

3. In a rolling mill, a curved trough for conveying metal, having its receiving and delivery ends substantially in axial alignment, the convex side of said trough being 5 lower than its concave side.

4. In a rolling mill, the combination with separated stands of reducing rolls, of means for feeding the metal continuously between and through said stands, a curved trough 10 adapted normally to convey the metal in its

passage between said stands, and means, operable in the event of an overfeed of metal, whereby to cause the overfeed loop to be deflected over the convex side of said trough.

15

Dated this 26th day of July, 1915.

VICTOR E. EDWARDS.
